US0D1098154S

(12) **United States Design Patent** (10) Patent No.: **US D1,098,154 S**
(45) Date of Patent: ** Oct. 14, 2025

(54) **DISPLAY SCREEN WITH A GRAPHICAL USER INTERFACE**

(71) Applicant: **TOSHIBA MITSUBISHI-ELECTRIC INDUSTRIAL SYSTEMS CORPORATION**, Tokyo (JP)

(72) Inventor: **Hiroki Shigeta**, Chuo-ku (JP)

(73) Assignee: **TMEIC CORPORATION**, Tokyo (JP)

(**) Term: **15 Years**

(21) Appl. No.: **29/928,930**

(22) Filed: **Feb. 16, 2024**

(30) **Foreign Application Priority Data**

Aug. 18, 2023 (JP) ..... 2023-016767 D

(51) **LOC (15) Cl.** **14-04**

(52) **U.S. Cl.**

USPC **D14/486**

(58) **Field of Classification Search**

USPC D14/485-495

CPC . A61B 1/00108; A61B 1/00032; G06F 9/442;

G06F 3/04886; G06F 2203/04805
